Primary Examiner — Kevin K Rudzinski*Assistant Examiner* — Jack Reickel(74) Attorney, Agent, or Firm — Banner & Witcoff, Ltd.CLAIM

The ornamental design for a display screen with icon, as shown and described.

DESCRIPTION

FIG. 1 is a front view of a display screen with icon showing a first embodiment of my new design; and, FIG. 2 is a second embodiment thereof.

The broken line showing of the display screen is for the purpose of illustrating environmental structure and forms no part of the claimed design.
